UNITED STATES PATENT OFFICE.

JAMES N. CHADWICK, OF CHICAGO, ILLINOIS.

INSTANTANEOUS STEAM WATER-HEATER.

1,196,520.

Specification of Letters Patent. Patented Aug. 29, 1916.

Application filed July 15, 1914. Serial No. 851,064.

To all whom it may concern:

Be it known that I, JAMES N. CHADWICK, a citizen of the United States of America, and resident of 10924 State street, Chicago, 5 Cook county, Illinois, have invented a certain new and useful Improvement in Instantaneous Steam Water-Heaters, of which the following is a specification.

My invention relates to the heating of 10 water for general purposes, but more particularly for lavatories and sinks, and especially for sleeping and other cars in which hot water is desired.

Generally stated, the object of my invention is to heat a stream of running water by steam.

A special object is to heat the running water by commingling the steam therewith in such a manner that the water, while 20 flowing, condenses the steam and absorbs the heat thereof before the point of discharge is reached. In other words, my invention contemplates an instantaneous steam heater for running water, and has for a further object the provision of certain details and features of construction tending to increase the 25 general efficiency and serviceability of a steam water heater of this particular character.

30 To these and other useful ends, my invention consists in matters herein shown and described and claimed.

In the accompanying drawings—Figure 1 is a side elevation of a steam water heater 35 embodying the principles of my invention. Fig. 2 is a plan of the same. Fig. 3 is a view similar to Fig. 1, but with certain portions of the structure shown in vertical section, the said section being taken approximately on line 3—3 in Fig. 4. Fig. 4 is a horizontal section on line 4—4 in Fig. 3. Fig. 5 is a horizontal section on line 5—5 in Fig. 3.

As thus illustrated, my invention comprises a fixture body or valve casing A having a water inlet α and a steam inlet α^1 of any suitable character. Within the said fixture or casing the steam and water passages come together in a discharge spout α^2 , which latter is like that of an ordinary faucet; but before the water and steam come together these two passages are controlled respectively by the valves B and C, and as these two valves are exactly alike the description of one will be sufficient. As shown in Fig. 3, therefore, the movable valve mem-

ber c rests upon the valve seat c^1 and is held down by a spring c^2 , being raised and lowered by the cam lever c^3 which is pivoted at c^4 to the upper end of the valve stem. The 60 valve B has a similar cam lever b which extends above the lever c^3 , and which is connected to the end of the latter by a vertically disposed pin or rod b^1 , or in any other suitable manner. With this arrangement, 65 the lever b must move down some distance before it strikes the lever c^3 , and consequently, and by reason of this lost motion connection the water valve is opened ahead of the steam valve, and cold water can be 70 drawn without opening the steam valve; but if warm water is wanted, then the lever b is pressed down until the lever c^3 opens the steam valve, and further downward pressure will then open the latter valve sufficiently to admit the full volume of steam 75 and thereby produce hot water.

The steam and water issuing from the discharge spout α^2 are preferably subjected to a commingling operation to prevent the 80 steam from escaping separately and without heating the water. This is accomplished by means of a chamber D which is screw threaded at its upper end to connect with the screw threaded lower end of the spout 85 α^2 , and which has its lower end provided with a vertically disposed tube E which projects a distance upwardly within the chamber, and has its upper end provided with a cone-shaped screen or perforated cap e the 90 apex of which is disposed centrally of the discharge spout above. The walls of the tube E within the interior of said chamber are provided with perforations or apertures e^1 , and with this arrangement the water and 95 steam are divided into small streams before escaping from the chamber into the passage e^2 of said tube. By thus breaking up the water into small streams or portions, and by compelling the steam to pass through 100 these small passages with the water, the heating of the latter is greatly facilitated. In other words, the tube E serves as a mixer, and causes the condensation of the steam by the water in a manner that would not be 105 possible with a single stream of water of full volume.

The plurality of small streams of water are combined or united within the passage e^2 , and the resulting discharge is a stream 110 of warm or hot water of the required volume and temperature. After passing through

the mixing device the water may be discharged into a lavatory without danger of discharging any unabsorbed steam—that is to say, the water will flow from the lower 5 end of the tube E in a steady stream and without showing any material amount of steam. In other words, this prevents the formation of steam pockets in the stream of running water, which would occur if no 10 means were employed for dividing the water into a multiplicity of small quantities which instantly become heated by the absorption of the steam. To prevent the pressure from splashing the water in the bowl, 15 a spreader e^s is disposed in the lower end of the tube E, being carried on the lower end of a stem e^4 which is fastened at its upper end to the wire screen or perforated cap e in a manner not to interfere with the 20 escape of the water and steam. This spreads the stream of water in all directions from the lower end of the nozzle or spout formed by the lower end of the tube E and prevents a forceful dashing of the water into 25 the bowl.

By the provision of the valves B and C the water and steam do not normally oppose each other, and hence neither one can back up the other when the water is not 30 running. If very hot water is wanted immediately, the hand can be allowed to engage the upper end of the pin or secondary handle b^1 as well as the main handle b^2 , and the simultaneous downward pressure on 35 both will open the water and steam valves at the same time, it being observed that the upper end of said pin has a head forming the secondary handle. The heel c^s of the lever c^s is rounded to prevent opening of 40 the steam valve C by raising the handle b^1 ; but the projecting heel b^s of the lever b bears upon the stuffing box of the valve B and opens this valve quite wide when the handle b^2 is raised, thus affording a full 45 stream of cold water. Downward motion of the handle b^1 alone will produce a discharge of steam only. When both valves are opened, the water and steam then naturally seek to escape through the spout a^2 , and the 50 two come together inside of the chamber D; but the breaking up of the water by the screen or strainer or perforated cone-shaped cap e , and by the perforations e^1 , precludes the escape of the water until after the steam 55 is thoroughly condensed, thus insuring an instantaneous and satisfactory heating of the running water. The steam and water are not confined after being thus mixed, but are immediately discharged downwardly 60 from the mixer into the bowl of the lavatory.

With the construction shown, therefore, both handles can be raised without opening the steam valve, for the reasons explained, 65 but such movement will open the cold water

valve and give a full discharge of cold water. On the other hand, as previously stated, the secondary handle can be moved downward from normal position without moving the main handle, when it is desired to operate the steam valve without opening the water valve, and this will give a discharge of steam alone, but the mixer serves in such case to prevent even dry steam under ninety pounds pressure from escaping in such condition that it would be dangerous. In other words, and even when the steam valve is opened alone, the steam after passing through the mixer becomes wet vapor and is practically harmless. Furthermore, and while the two handles are operable separately and independently of each other, to a certain extent, when such is necessary or desirable, still either handle can be operated by the other as pressure on the main handle will eventually depress the secondary handle, and a pressure of the secondary handle only would eventually result in a depression of the main handles. Thus either warm water or cold water may be 90 drawn by simply one operation.

I do not limit myself to the exact construction shown and described.

What I claim as my invention is:—

1. Apparatus for mixing steam with running water to heat the latter, comprising a steam valve, a cold water valve, a main handle for said water valve, a secondary handle for said steam valve, said handles being interconnected to cause the operation of both by merely pressing down on the main handle, separate passages leading to said valves, and means to discharge the mixture formed when both valves are open, said interconnection having some lost-motion to 100 permit opening of the water valve ahead of the steam valve.

2. Apparatus for mixing steam with running water to heat the latter, comprising a steam valve, a cold water valve, a main handle for said water valve, a secondary handle for said steam valve, said handles being interconnected to cause the operation of both by merely pressing down on the main handle, separate passages leading to 110 said valves, and means to discharge the mixture formed when both valves are open, said interconnection having some lost-motion to permit opening of the water valve ahead of the steam valve, and said lost-motion permitting opening of the steam valve 120 alone when the secondary handle only is depressed.

3. Apparatus for mixing steam with running water to heat the latter, comprising a 125 steam valve, a cold water valve, a main handle for said water valve, a secondary handle for said steam valve, said handles being interconnected to cause the operation of both by merely pressing down on the 130

main handle, separate passages leading to said valves, and means to discharge the mixture formed when both valves are open, said interconnection having some lost-motion to permit opening of the water valve ahead of the steam valve, and a screw for adjusting said lost-motion to regulate the proportion of steam and water.

4. Apparatus for mixing steam with running water to heat the latter, comprising a steam valve, a cold water valve, a main handle for said water valve, a secondary handle for said steam valve, said handles being interconnected to cause the operation of both by merely pressing down on the main handle, separate passages leading to said valves, and means to discharge the mixture formed when both valves are open, said interconnection having some lost-motion to permit opening of the water valves ahead of the steam valve, springs for yieldingly holding said valves closed, and means for adjusting the normal position of one handle to regulate the relative compression of said springs.

5. Apparatus for mixing steam with running water to heat the latter, comprising a steam valve, a cold water valve, a main handle for said water valve, a secondary handle for said steam valve, said handles being interconnected to cause the operation of both by merely pressing down on the main handle, separate passages leading to said valves, and means to discharge the mixture formed when valves are open, said interconnection having some lost-motion to permit opening and closing of the water valve ahead of the steam valve, and the secondary handle being movable downward alone to produce a discharge of steam only.

6. Apparatus for mixing steam with running water to heat the latter, comprising a steam valve, a cold water valve, a main handle for said water valve, a secondary handle for said steam valve, said handles being interconnected to cause the operation of both by merely pressing down on the main handle, separate passages leading to said valves, and means to discharge the mixture formed when both valves are open, said interconnection having some lost motion to permit opening of the water valve ahead of the steam valve, and said main handle being movable upward only to cause a discharge of cold water alone.

7. Apparatus for mixing steam with running water to heat the latter, comprising a steam valve, a cold water valve, a main handle for said water valve, a secondary handle for said steam valve, said handles being interconnected to cause the operation of both by merely pressing down on the main handle, separate passages leading to said valves, and means to discharge the mixture formed when both valves are open, said

interconnection having some lost-motion to permit opening of the water valve ahead of the steam valve, and the two handles being operable by pressure on both to produce hot water at once.

8. Apparatus for mixing steam with running water to heat the latter, comprising a steam valve, a cold water valve, a main handle for said water valve, a secondary handle for said steam valve, said handles being interconnected to cause the operation of both by merely pressing down on the main handle, separate passages leading to said valves, and means to discharge the mixture formed when both valves are open, said interconnection having some lost-motion to permit opening of the water valve ahead of the steam valve, said handles having levers which extend one over the other, and said connection including a pin fixed on one lever and extending loosely through the other lever.

9. Apparatus for mixing steam with running water to heat the latter, comprising means to separately supply steam and water, a mixing device for commingling the water and steam, a passage leading from said means, said device including a cone-shaped strainer disposed immediately below the outlet of said passage, a tube leading downward from said strainer, and a chamber inclosing said strainer.

10. Apparatus for mixing steam with running water to heat the latter, comprising means to separately supply steam and water, a mixing device for commingling the water and steam, a passage leading from said means, said device including a cone-shaped strainer disposed immediately below the outlet of said passage, a tube leading downward from said strainer, and a chamber inclosing said strainer, said tube having inlet openings in the sides thereof within said chamber.

11. Apparatus for mixing steam with running water to heat the latter, comprising means to separately supply steam and water, a mixing device for commingling the water and steam, a passage leading from said means, said device including a cone-shaped strainer disposed immediately below the outlet of said passage, a tube leading downward from said strainer, and a chamber inclosing said strainer, a rod depending in said tube from said strainer, and a spreader on the lower end of said rod, said spreader being disposed at the lower end of said tube.

12. Apparatus for mixing steam with running water to heat the latter, comprising means for supplying running water and steam, and a mixing device for commingling the water and steam to heat the running water by condensation of the steam, a discharge spout for the heated water, and a

spreader in the end of said spout, said device including a strainer to which the upper end of said spreader is fixed in position.

13. Apparatus for mixing steam with running water to heat the latter, comprising a steam valve, a cold water valve, a main handle for said water valve, a secondary handle for said steam valve, said handles being interconnected to cause the operation of both by merely pressing down on the main handle, separate passages leading to said valves, and means to discharge the mixture formed when both valves are open, said interconnection having some lost motion to permit opening of the water valve ahead of the steam valve, and said lost-motion connection causing the steam valve to close ahead of the water valve when the handles are released.
14. Apparatus for mixing steam with running water to heat the latter, comprising a steam valve, a cold water valve, a main handle for said water valve, a secondary handle for said steam valve, said handles being interconnected to cause the operation of both by merely pressing down on the main handle, separate passages leading to said valves, and means to discharge the mixture formed when both valves are open, said interconnection having some lost motion to permit opening of the water valve ahead of the steam valve, said main handle being disposed above the secondary handle, and the steam valve being operable by further downward movement of the secondary handle after the main handle is depressed.
15. Apparatus for mixing steam with

running water to heat the latter, comprising a steam valve, a cold water valve, a main handle for said water valve, a secondary handle for said steam valve, said handles being interconnected to cause the operation of both by merely pressing down on the main handle, separate passages leading to said valves, and means to discharge the mixture formed when both valves are open, said interconnection having some lost motion to permit opening of the water valve ahead of the steam valve, and said secondary handle being operable to further open the steam valve while the main handle is fully depressed.

16. Apparatus for mixing steam with running water to heat the latter, comprising a steam valve, a cold water valve, a main handle for said water valve, a secondary handle for said steam valve, said handles being interconnected to cause the operation of both by merely pressing down on the main handle, separate passages leading to said valves, and means to discharge the mixture formed when both valves are open, said interconnection having some lost motion to permit opening of the water valve ahead of the steam valve, and the upward movement of both handles serving to open the cold water valve without opening the steam valve.

Signed by me at Chicago, Cook county, Illinois, this 6th day of July, 1914.

JAMES N. CHADWICK.
